Warren E. Willis.
ATTORNEY

UNITED STATES PATENT OFFICE.

CHRISTIAN MUENTENER, OF BOGOTA, NEW JERSEY.

STAIR ROD.

Application filed November 30, 1927. Serial No. 236,686.

This invention relates to devices for holding carpets on stair-ways whereby such coverings may be maintained in close adjustment.

5 Stair coverings usually consist of a single strip of carpet, narrower than the width of the stairs, and applied over the treads and risers, being held by tacks at the bottoms of the risers or by rods through which are passed nails or like securing means of a fixed, enduring nature, making the removal of the carpet difficult and mutilating the stair way in either case.

10 It is therefore one of the objects of this invention to provide a stair rod that is fully capable of securing a carpet in place on a stair-way, without driving nails or the like, no tools being required, and which can be as readily removed to release the carpet, 15 either operation taking the briefest possible time.

15 A further feature is in the provision of a stair rod capable of being applied or removed without mutilation or disfigurement of the 20 carpet or stair-way, the operation being so simple that it can be accomplished by a novice without difficulty.

25 Another purpose is to produce a stair rod composed of essentially simple and inexpensive parts, light in weight, having abundant 30 strength and possessing a neat and attractive appearance.

35 These several advantageous objects are obtained by the novel construction and combination of parts hereinafter described and shown in the annexed drawing forming a material part of this disclosure, and in which:—

40 Figure 1 is a front elevational view of a portion of a conventional stair-way illustrating the application of the invention.

Figure 2 is a side elevational view of the same.

45 Figure 3 is a partial side view of an embodiment of the stair rod, shown in a raised position prior to attachment, parts being in section.

Figure 4 is a similar view of the rod as extended straight.

50 In Figures 1 and 2 a pair of inclined sides, ordinarily made of wood, are designated by the numeral 5 between which are a flight of stairs composed of horizontal treads 6 and risers 7, shown as covered by a carpet 8, of lesser width than the distance between the 55 stair side, all being of the usual and well known construction.

The invention consists of a stair rod, generally designated by the numeral 9 and shown in detail in Figures 3 and 4.

Each stair rod unit consists of two tubular 60 sections 10, each section having rigidly secured in one end a plug 11 which is entered within the tube to leave a short space at the end, and fixed in the plugs are eyes 12 interengaged in the manner of a hinge, permitting the tubes to be disposed at an angle, as shown in the broken lines on the top step in Figure 1, and better in the detail view in Figure 3.

A plurality of spaced transverse perforations 13 are made in the opposite outer portions of the tubes, in which are slidably engaged relatively short tubes or rods 14, the same having a single transverse opening through which is passed a headed pin 15 to 75 adjustably retain the element 14 within the tube.

Set in the outer ends of the adjustable elements 14 are the shanks of convex cushion members 16, preferably made of rubber, and 80 extending axially outward from these members are sharply pointed fixed spurs 17, adapted to pierce the stair sides 5 to the limit of the cushions 16.

In order to hold the tubular members 10 in 85 alignment when fixed in position, a telescopic tube or elongated sleeve 18 is arranged slidably thereon, the same extending over the hinged central joint, acting to maintain the same rigid when extended straight out and also to completely obscure the joint.

90 In operation the elements 14 are adjusted by the pins 15 so that the distance between the cushions 16, when the device is extended straight, will closely approximate the distance between the sides 5 of the stair-way.

95 Thereupon, the carpet having been adjusted over the steps, the sleeve 18 is moved to one side or the other, the joint formed by the eyes 12 turned upward and the spurs 17 set in the wood work in such manner as to press the carpet into the angle between the tread and riser of the stair.

100 Obviously by exerting moderate pressure upon the raised joint, the rod will become straight, permitting the sleeve to be moved over the joint and retain the carpet in its proper adjustment.

105 It will be equally apparent that the carpet can be removed by reversing the foregoing operations and that no possible damage is done the carpet or the wood work, other than

the mere perforations of the spurs 17, as the cushions 16 provide against abrasion.

Notwithstanding the simple character of the invention, it is not desired to be confined 5 to the exact construction shown, as minor modifications can well be made within the scope and character of the appended claims.

Having thus described my invention what I claim as new and desire to secure by Letters Patent, is:—

10. 1. A stair rod composed of two tubular sections jointed at one end to permit relative angular motion, rods telescopically engaged in the opposite ends of said tubular sections, means to retain said rods in adjustment therein, cushion elements at the outer ends of said rods, spurs protruding from said cushions, and a sleeve slidable over the joint between said sections.
20. 2. A stair rod composed of a pair of tubes having plugs fixed in their adjacent ends, eyes set in said plugs, said eyes being interengaged to permit relative angular movement of the tubes, a sleeve slidable over the adjacent ends 25 of said tubes, rods adjustably secured in the opposite ends of the tubes, and sharply pointed spurs at the outer ends of said rods.

3. A stair rod composed of two equal members having a universal joint connecting therebetween, a slide on said members to retain the joint rigid when moved thereover, adjustable element slidable in said members, cushions at the outer ends of said members, and prongs extending axially through the 30 cushions.

35. 4. A stair rod comprising a pair of tubes having a universal joint therebetween, means for maintaining said joint rigid when the tubes are in register, telescopic rods movable in said tubes, means for fixing said rods in adjustment, cushions on the ends of said rods, and sharply pointed prongs extending from said cushions.

40. 5. A stair rod composed of two universally jointed members, rods adjustably secured therein, said rods being adapted to extend longitudinally the full width of a stairway, 45 cushions at the ends of said rods to engage the sides of the stair way, and means in said cushions to enter the stair way sides to retain the rod fixedly therebetween.

50. In testimony whereof I affix my signature.

CHRISTIAN MUENTENER.
